X-RAY UNIT OR THE LIKE

Robert H. Ensign, Bronxville, and Alban Gifford Jackson, New York, N. Y., assignors to Ritter Company, Inc., a corporation of Delaware

Application November 13, 1956, Serial No. 43,726

Term of patent 14 years

(Cl. D61—1)

FIG. 1.

FIG. 2.

Fig. 1 is a perspective view of an X-ray unit showing our new design with the support arm in extended position; and

Fig. 2 is a partial view of Fig. 1, also in perspective, showing the extensible support arm in a substantially collapsed position.

The opposite side of the unit is substantially like the side shown.

The essential features of our design reside in the solid line portions.

We claim:

The ornamental design for an X-ray unit or the like, substantially as shown and described.
